LIGHTING FIXTURE

Marcus E. Kanter, Cleveland, Ohio, assignor to
Railley Corporation, Cleveland, Ohio, a corpora-
tion of Ohio

Application July 19, 1940, Serial No. 346,380

3 Claims. (Cl. 248—224)

This invention relates to an electric lighting fixture of the "pin-it-up" type adapted to be detachably supported upon a wall.

One of the objects of this invention is to provide a lighting fixture which includes a combination supporting hook and hanger bar for maintaining the fixture in a vertical position on the wall and which prevents accidental tipping or tilting thereof.

Another object of the invention is to provide a combination supporting hook and hanger bar for lamps of the character described which is unique in construction and well adapted for use with many styles and types of lamps.

A further object of the invention is to provide a lighting fixture adapted to be hung on a wall and which comprises a plaque which is adapted to be detachably secured to a hanger bar, the hanger bar being secured to the wall adjacent its opposite ends and having a hook adjacent the upper end thereof, the lower end of the hanger bar being provided with a deflected portion which engages the plaque adjacent its central portion and holds it against accidental displacement or tipping.

Another object of the invention is to provide a lighting fixture having the above described distinguishing features and characteristics and which is well adapted for quantity production at comparatively low cost.

Further and more limited objects of the invention will appear as the description proceeds and by reference to the accompanying drawing in which Fig. 1 is a view in front elevation of my improved lamp bracket; Fig. 2 is a vertical sectional view of the lamp bracket shown in Fig. 1; Fig. 3 is a horizontal sectional view on the line 3—3 of Fig. 1; Fig. 4 is a perspective view of the hook which supports the plaque; Fig. 5 is a perspective view of the hanger bar removed from the lamp bracket and Fig. 6 is a perspective view of a modified form of hanger bar.

Referring now to the drawing, the lighting fixture consists essentially of a plaque 1 which is preferably generally oval in shape but which may be of any desired design. The plaque is preferably shaped in section as shown most clearly in Figs. 2 and 3 and has on the rear face thereof an integral flange 2 having an opening 3 therein and which is shaped to provide a pair of converging side walls. Carried by the rear face of the plaque and preferably formed integral therewith are a pair of spaced projections 4 and 5 which are disposed a considerable distance below the flange 2. Carried by the plaque and extending upwardly

therefrom is a supporting arm 6 which is secured to the plaque by means of bolts 7 and 8. The arm 6 is preferably somewhat oval in shape and is adapted to receive therein a light cord 9 which extends through an opening provided in the plaque and thence downwardly through a notch or opening provided in the lower edge of the plaque. The supporting arm 6 is adapted to receive and support a lamp socket, not shown. In order to secure the lighting fixture to a wall and to hold it against tipping, I have provided a hanger bar 10 shown in detail in Fig. 5 and which has a pair of openings 11 and 12 therein disposed adjacent opposite ends thereof. The hanger bar has a pair of tongues 13 and 14 cut out and bent upwardly therefrom, as shown most clearly in Fig. 5; and the lower portion of the hanger bar is deflected outwardly as shown at 15. The reference character 16 designates a hook for supporting the hanger bar and plaque. When it is desired to secure the lighting fixture to a wall, the hanger bar and hook are assembled, as shown in Fig. 2, and the upper end of the hanger bar is loosely secured to the wall by means of a pin or nail 17. The hanger bar, being loosely supported from its upper end, naturally hangs in a vertical position. The lower end of the hanger bar is then secured in place by a small nail or brad 18. The nail 17 may then be driven home with assurance that the hanger bar has been secured to the wall in a vertical position. The hook 16 is held against sidewise displacement by being disposed between the ears 13 and 14. The plaque may then be hung on the hook in the position shown in Fig. 2. It is to be noted that the flange 2 and the projections 4 and 5 are completely hidden by the plaque. The inclined walls of the flange 2 serve to direct the hook 16 into the opening 3 in the flange. The projections 4 and 5 are disposed on opposite sides of the deflected portion 15 of the hanger bar and serve to hold the plaque against sidewise displacement. It will be noted that the hanger bar extends a substantial distance and that the plaque is secured to the hanger bar at two vertically spaced points, so that there can be no accidental tipping or tilting of the lighting fixture or plaque. When it is desired to remove the plaque, it is merely lifted off the hook, leaving the hanger on the wall.

In Fig. 6 there is disclosed a slightly modified form of hanger bar as indicated by the reference character 20. This hanger bar has a tongue 21 cut out and bent upwardly therefrom as shown in Fig. 6 to provide a hook, and is also provided with a deflected portion 22. The hook serves to sup-

port the plaque and avoids the necessity for a separate hook, such as is used with the hanger bar shown in Fig. 5.

It will now be clear that I have provided a lighting fixture which will accomplish the objects of the invention as hereinbefore stated. Various changes may be made in the details of construction and arrangement of parts without departing from the spirit of my invention and the embodiments of the invention herein disclosed are to be considered merely as illustrative and not in a limiting sense, as the invention is limited only in accordance with the scope of the appended claims.

Having thus described my invention, what I claim is:

1. A lamp bracket comprising an elongated plaque adapted to be secured upon a wall, a hanger bar for supporting said plaque in vertical position upon a wall, a hook disposed adjacent the upper end of said hanger bar, a portion of said hanger bar being deflected outwardly adjacent the lower end thereof, said plaque having means formed integrally therewith for engaging said hook and additional means also formed integrally with said plaque adapted to engage the deflected portion of said hanger bar so as to hold said plaque in vertical position on the wall.

2. A lamp bracket comprising an elongated plaque adapted to be secured upon a wall, a hanger bar adapted to receive and detachably support said bracket, said hanger bar having an integrally formed hooked end portion and an outwardly deflected portion disposed adjacent the opposite end thereof, said lamp bracket having formed integrally therewith a hook guiding and receiving flange adjacent the upper end thereof and means formed integrally with said bracket and disposed adjacent the central portion thereof adapted to engage said outwardly deflected portion whereby to hold said lamp bracket in vertical position on the wall but permitting removal of the lamp bracket independent of said hanger bar.

3. A lamp bracket comprising an elongated plaque the rear face of which has an apertured integral flange thereon shaped to provide inclined side walls and also provided on its rear face with a pair of spaced projections disposed below the center thereof, a support for said plaque comprising a thin bar having a hook adjacent the upper end thereof adapted to be engaged by said integral flange and an outwardly deflected portion adapted to be engaged by said pair of projections.

MARCUS E. KANTER.
